UNITED STATES PATENT OFFICE.

CARL G. THOMPSON, OF KNOXVILLE, TENNESSEE.

DRIVING MECHANISM.

1,403,923.

Specification of Letters Patent. Patented Jan. 17, 1922.

Application filed July 22, 1921. Serial No. 486,783.

To all whom it may concern:

Be it known that I, CARL G. THOMPSON, a citizen of the United States, residing at Knoxville, in the county of Knox and State 5 of Tennessee, have invented certain new and useful Improvements in Driving Mechanism, of which the following is a specification.

This invention relates to mechanism specially adapted for gyrating shaking bolts or 10 chop graders which are provided with sieves and are suspended from stationary supports; and it consists in the novel construction and combination of the parts hereinafter fully described and claimed whereby the sieve 15 casing is placed out of balance gradually and is gyrated without any jerking movements.

In the drawings, Figure 1 is a side view of 20 a portion of a gyratory sieve casing, showing how the device is applied to it. Fig. 2 is a side view of a driving mechanism constructed according to this invention. Fig. 3 is a plan view of the same with the top plate of the frame removed. Fig. 4 is a plan view, 25 similar to Fig. 3, showing a modification of the mechanism shown in Figs. 2 and 3.

The sifter casing 5 is suspended from rafters 6, or other supports, by resilient rods 7 which permit the casing to gyrate in a 30 horizontal plane. The sieves and other devices inclosed in the casing are of any approved kind.

A vertical shaft 8 is journaled in similar 35 bearings 9 on the top and bottom parts of the casing, and is revolved by a belt pulley 10. Two similar driving mechanisms are preferably provided, and are secured to the shaft 8 above and below the casing.

Each mechanism has a frame 12 which is 40 secured to the shaft 8, and which is preferably formed of upper and lower plates 14 and 15 provided with one or more suitable distance pieces 16. Two pins 17 are arranged in the frame 12 substantially parallel 45 to each other and to the shaft 8, and at equal distances from the shaft 8 and upon one side of it. Arms 18 are pivoted on these pins, and have hubs 19 provided with intergearing teeth 20, so that the arms are constrained to 50 move simultaneously in opposite directions on their pivots. These arms 18 have weights at their free ends, and these weights 21 are preferably formed of boxes which are filled with lead or other heavy material, the quantity of which may be varied and adjusted. The arms 18 have antifriction rollers 22 at

their outer parts which run on the lower plate 15, which is flat or which has a flat track for the rollers to run on, so as to reduce the friction.

60 Helical springs 24 are secured to the arms 18 at one end, and at the other end to the frame. The frame preferably has an anchor bar 25 which projects horizontally on the longitudinal center line 26 drawn through the axis of the driving shaft 8, and midway between the two pivot pins 17. This anchor bar is preferably bolted to the frame at one end, and it has a series of holes 27 at its other end portion, arranged at different distances from the center line 26. The springs 24 are connected to the anchor bar by pins 28, and the object of having a series of holes for the pins is to enable the springs to be arranged at different angles with each other 70 and the center line 26, so that they may work to the best advantage.

75 The springs may also be connected to the arms 18 at different points, if desired. A weight 30 is secured to the frame 12 on the center line 26, and on the opposite side of the shaft 8 from the anchor bar 25. This weight substantially balances the mechanism when the parts are in their normal position, and when the weights 21 of the arms 18 are 80 on the same side of the cross center line 31 of the driving shaft 8 as the anchor bar 25, as shown in full lines in Fig. 3. The cross center line 31 of the driving shaft is arranged at a right angle to the longitudinal 85 center line 26.

90 When the driving shaft is revolved, the weighted arms 18 are moved gradually by centrifugal force in a horizontal plane across the cross center line 31 to the positions shown 95 in dotted lines in Fig. 3, in which the said arms are radial of the driving shaft. As the driving shaft is vertical, and as the pivot of each arm 18 is also vertical, and as the arms move in a horizontal plane, the action of this 100 driving mechanism is very smooth, and free from jerks, and the arrangement of the parts is such that the mechanism takes up very little room vertically.

105 In the modification shown in Fig. 4, the two weighted arms 18 are pivoted on a single vertical pivot pin 37 secured to the frame 12 and arranged parallel to the vertical driving shaft 8. The weighted arms 18 are constrained to move simultaneously in opposite 110 directions by means of two connecting-rods 38 which are pivoted to the arms at one end

by pins 39, and at the other end to a slide 40 by pins 41. The slide 40 slides on a guide rod 42 secured to the frame 12 and its anchor bar, and the arms are retracted by a helical spring 43 arranged in compression between the slide 40 and an abutment 44 on the frame.

What I claim is:

1. The combination, with a gyratory device, of a vertical driving shaft journaled in the said device, and a driving member revolving with the said shaft and working on a vertical pivot in a horizontal plane, said driving member being moved into an unbalanced position by centrifugal force when revolved, and operating to gyrate the device.

2. The combination, with a gyratory device, of a vertical driving shaft journaled in the said device, and a pair of weighted arms revolving with the said shaft, each arm working on a vertical pivot and in a horizontal plane, said arms being moved over the cross center line of the driving shaft into an unbalanced position by centrifugal force as the shaft is revolved.

3. The combination, with a gyratory device, of a vertical driving shaft journaled in the said device, and a pair of weighted arms pivoted substantially parallel to and arranged on one side of the said shaft and revolved by it in a horizontal plane, said arms being moved into an unbalanced position by centrifugal force as the shaft is revolved.

4. The combination, with a gyratory device, of a vertical driving shaft journaled in the said device, a frame secured on the said shaft and a pair of weighted arms pivoted to the said frame by vertical pivots and arranged on one side of the said shaft.

5. The combination, with a gyratory device, of a vertical driving shaft journaled in the said device, a pair of weighted arms pivoted substantially parallel to and arranged on one side of the said shaft and revolved by it in a horizontal plane, and means which constrain the said arms to move pivotally in opposite directions.

6. The combination, with a gyratory device, of a vertical driving shaft journaled in the said device, a pair of weighted arms pivoted substantially parallel to and arranged on one side of the said shaft and revolved by it in a horizontal plane, and in-

tergearing toothed members which constrain the said arms to move pivotally in opposite directions.

7. The combination, with a gyratory device, of a vertical driving shaft journaled in the said device, a pair of weighted arms revolving with the said shaft, each arm working on a vertical pivot and in a horizontal plane, and springs which restore the said arms to their normal balanced positions when the driving shaft ceases to revolve.

8. The combination, with a gyratory device, of a vertical driving shaft journaled in the device, a frame secured on the said shaft, a pair of weighted arms revolving with the said shaft, each arm working on a vertical pivot and in a horizontal plane, and helical springs secured to the arms at one end and to the frame at the other end and operating to restore the said arms to their normal balanced positions when the driving shaft ceases to revolve.

9. The combination, with a gyratory device, of a vertical driving shaft journaled in the said device, a pair of weighted arms pivoted substantially parallel to and arranged on one side of the said shaft, an anchor bar also revolving with the said shaft and projecting on a longitudinal center line drawn through its axis and midway between the pivots of the said arms, and helical springs arranged between the said arms and the anchor bar at an angle to the said center line and operating to restore the said arms to their normal balanced positions when the driving shaft ceases to revolve.

10. The combination, with a gyratory device, of a vertical driving shaft journaled in the said device, a pair of weighted arms pivoted substantially parallel to and arranged at one side of the said shaft, and a weight also revolving with the said shaft and projecting on a longitudinal center line drawn through its axis and midway between the pivots of the said arms, said weight operating to balance the said arms when in their normal positions on the other side of the cross center line of the said shaft from the said weight.

In testimony whereof I have affixed my signature.

CARL G. THOMPSON.
